Inventor:

Walter Königsberger

UNITED STATES PATENT OFFICE

WALTER KÖNIGSBERGER, OF BERLIN, GERMANY

GARTER

Application filed October 20, 1925, Serial No. 63,620, and in Germany August 11, 1925.

My invention relates to garters or hose supporters, more especially such as are adapted to support the leg portion of socks and which comprise a continuous strip of elastic webbing and a self-securing clasp. It is an object of my invention to provide a garter of this kind, which is distinguished by simplicity of construction, by cheapness, and by the ease with which it can be adjusted by the wearer and the strip of webbing replaced.

My new and improved garter offers finally the special advantage, that the adjustment to the desired length may be done without the necessity of overcoming friction resistance or other resistances by passing the ribbon straight-way through a closed slot in the clamping device, and that after finishing the adjustment the ribbon may be fixed against any further undesired sliding in a most easy way by a small movement of the free end of the ribbon.

In the accompanying drawings I have shown an embodiment of my invention, wherein

25 Figure 1 is a front view of the clasp;

Figures 2 and 3 are a front view and a side view respectively of a soft, pliable member cooperating with the clasp in securing the strip of webbing in position;

30 Figures 4 and 5 are a side view and a front view, respectively, of the several parts forming the garter, as assembled;

Figure 6 is a perspective view showing how the new garter may be used as a ring shaped garter encircling the leg.

Referring to the drawings, the new garter, according to the embodiment of my invention, comprises a strip of webbing *k*, preferably elastic, and two clasps, one at each end of the strip *k*, each being formed of a rigid plate *a* (Fig. 1), and a pliable plate *g* (Figs. 2 and 3).

The rigid plate *a* may be made of metal, celluloid or some other suitable, substantially rigid, material. It has the form of an oblong tongue presenting a keyhole-shaped aperture. This aperture extends substantially from one end to about the middle of the plate *a*. Between it and the other end of the plate is formed a transverse slot *d* having a length

and width substantially equalling the width and thickness of the strip of webbing *k* to be held therein. The end of the plate *a* adjoining the slot *d* is formed into a pair of inwardly directed hooks *f*. The distance between the base portions of these hooks is substantially equal, the distance between their free inner ends slightly inferior, to the width of the strip, whereby the strip of webbing, on being placed with its lateral portions upon the hooks, will under the action of a slight pull slip in of itself, the lateral portions giving way in a resilient manner and after having overcome the resistance offered by the inner ends of the hooks, returning to their normal position automatically. Fig. 5 shows the strip of webbing in position in the indenture *e*. The strip of webbing being passed first through the slot *d* and its free end introduced into the notch between the hooks and is doubled up so as to extend in parallel to the plate *a*. If now a pull is exerted on the main portion of the strip, it will apply itself against that part of this portion which is acted upon by the hook-shaped projections *f*, *f* and will create strong friction between this part and the said projections, thereby counteracting any tendency of slipping and firmly locking the strip in the plate. On the other hand the strip can be unlocked and readjusted by the wearer with the greatest ease by merely pulling the free end of the strip into a position at right angles to the plate, thereby causing the lateral portions of the strip in contact with the projections *f* to double up and slip past these projections and to escape from the notch altogether. In this position of the parts the strip can easily be adjusted relative to the plate *a* by pulling at one end or the other, and can be locked anew in its readjusted position by once more placing the free end across the notch and causing it to enter same.

The locking of the strip in the plate *a* is assisted by the pliable plate *g*, and which is attached to the plate *a* by means of a thread passed through registering holes *n*, *n* in the plates *a* and *g*. The pliable plate *g* has formed therein a transverse slot *z* registering, when the plate is fixed in position, with the

slot *d* in plate *a*, and the strip of webbing *k* is made to pass through both these slots and on being doubled up, as shown in Fig. 4, exerts pressure on the end of the plate *g*, which adjoins and slightly projects across the notch *e*, pressing same against the notch and against that part of the strip *k*, which extends therethrough, thereby reinforcing the frictional engagement between the strip and the hook-shaped projections *f*, *f*. At the same time the end portion of plate *g* prevents contact between the parallel portions of the strip and also prevents frictional displacement of the free portion by the stretched portion when the tension of this latter varies in use.

As shown more particularly in Figs. 1 and 2, the distance between the sewing holes *n* and the narrow edge in the plate *g* is greater than the distance between the sewing holes and the edge bordering the notch *e* in plate *a*, so that the narrow edge of the plate *g* will project beyond the edge bordering notch *e* and will partly cover this notch on one side, thereby forcing the free end of the strip against the hooks *f*.

Apart therefrom the edges of the slot formed in the plate *g* also tend to frictionally engage the strip and to prevent its sliding relative to the plate *a*, unless acted upon in the direction at right angles to the plate.

The free end of the pliable plate *g* carries a knob *h* adapted to be introduced in the wider part of the keyhole-shaped aperture *b* and to slip into the narrower part thereof, gripping in a well known manner between it and the plate the marginal portion of the sock or other garment to be supported.

In the embodiment shown in the drawings the plate *a* at the other end of the strip is formed without the notch and hooks, the strip of webbing being permanently held in the closed slot of the plate by its end being thickened in some suitable manner, as shown at *o*, so as to be unable to escape from the slot. The other end can be thickened in a similar manner, as shown at *m*.

If it is desired to use the garter in the form of a belt encircling the leg above or below the knee, the free end of the strip can be passed through between the assembled plates *a* and *g*, as shown for instance in Fig. 6.

I wish it to be understood that I do not desire to be limited to the exact details of construction shown and described for obvious modifications will occur to a person skilled in the art.

I claim:—

1. A garter comprising a strip of webbing, a substantially rigid slotted member engaging said strip for free sliding movement thereon, a transverse bar bordering the slot in said member and a pair of inwardly directed hooks surmounting the ends of said bar, a pliable member associated with the slot in said rigid member, so as to brake the sliding

movement of said member relative to said strip, the free end of said strip being engaged by said hooks and the free edge of said pliable member being arranged to force said free end against said hooks.

2. In a garter, a clasp comprising a rigid plate and a pliable plate, means securing said plates together intermediate their ends, said plates having transverse slots disposed forwardly of said securing means, said rigid plate having rearwardly and inwardly extending fingers forming an open slot rearwardly of said securing means, said pliable plate having a rearwardly extending portion projecting under said open slot, and an elastic webbing strip looped first upwardly through said first mentioned slots in said plates, then rearwardly over said securing means, and then downwardly through said open slot in said rigid plate beneath said fingers and above said extended portion of said pliable plate, whereby said strip is frictionally held between said fingers and said extended portion of said pliable plate.

3. In a garter, a clasp comprising a pair of plates, means securing said plates together intermediate their ends, said plates having transverse slots forwardly of said securing means, one of said plates being of rigid material and having rearwardly and inwardly extending fingers forming an open slot therebehind, the other of said plates being of soft material and having an extended portion projecting under said open slot, the opening between the ends of said fingers being greater than the portion of the slot behind either of the inwardly turned fingers, whereby said strip may be sprung into said open slot for frictional engagement with said extended portion of said soft plate, or sprung out of said open slot for adjustment purposes.

4. In a garter, a clasp comprising a pair of plates secured together intermediate their ends, said plates being provided with substantially registering slots, one of said plates being of rigid material and having rearwardly and inwardly extending fingers forming an open slot therebehind, the other of said plates being of soft material and having an extended portion projecting beneath said open slot, an elastic strip of webbing the width of which substantially equals the length of said slots looped through said first mentioned slots and said open slot, the distance between the ends of said fingers being such with relation to the width of the strip that the strip may be sprung between them without material longitudinal creasing, and will be retained in position behind them in frictional contact with said extended portion of said soft plate.

In testimony whereof I have affixed my signature.
